UNITED STATES PATENT OFFICE

JOSEPH F. BUSHEE, OF JERSEY CITY, NEW JERSEY

SMOKING PIPE

Application filed August 27, 1928. Serial No. 302,376.

This invention relates to improvements in smoking pipes.

The primary object of the invention resides in a smoking pipe in which the smoke from the bowl is moderately cooled in its passage through the stem so as not to irritate the tongue and mouth of a smoker, and in which tobacco bits and moisture are trapped to prevent them from entering the restricted bore 10 of the stem and obstructing the free passage of smoke therethrough.

Another object is to provide a smoking pipe in which tobacco bits and moisture may be trapped, and after use, the same may be 15 blown out through the bowl by a blast of air to keep the pipe in a clean dry condition.

A further object is the provision of a smoking pipe having a tube mounted in the stem thereof, the inner end of the tube being flared 20 and which extends into a pocket having communication with the bowl, the flared end being disposed in spaced relation to cause the smoke to pass through the pocket before entering the tube whereby tobacco bits drawn 25 from the bowl into the pocket will accumulate in the latter.

With these and other objects in view, the invention resides in certain novel construction and combination and arrangement of 30 parts, the essential features of which are hereinafter fully described, are particularly pointed out in the appended claims, and are illustrated in the accompanying drawings, in which:—

Figure 1 is a vertical longitudinal sectional view through my improved smoking pipe.

Figure 2 is a detail perspective view of the tube.

Figures 3, 4 and 5 are vertical longitudinal 40 sectional views of various modifications.

Referring to the drawings by reference characters, the numeral 10 designates a smoking pipe which includes the usual bowl 11, stem 12, and mouthpiece or bit 13 which 45 movably fits into the stem. The outer end of the stem 12 is provided with an enlarged bore 14 which communicates with pockets 15 of a reduced diameter in Figures 1 and 4 into which ducts 16 enter. The ducts 16 open 50 into the bottom of the bowl and in Figures

2 and 3 they communicate direct with the bores 15 of the respective pipes.

In Figures 1, 2 and 5 of the drawings, I have shown a length of tube 17 which is uniform throughout its length but which is flared outward at one end as at 18, the flared end of the tube shown in Figure 1 terminating within the pocket 15 in spaced relation to the walls thereof. Fixed to the tube adjacent the flared end is a bearing collar 19 which may be secured by sweating the same thereon or by a tight friction fit. The collar is provided with stepped annular flanges 20 and 21 and in Figure 1 of the drawings, the smaller flange 20 fits into the pocket 15 while the larger flange 21 abuts the shoulder formed between the pocket and the bore 14. The collar serves as a support or bearing for the flared end of the tube, while the opposite end fits into the bore 22 in the mouthpiece 13 and 70 is supported thereby. The intermediate portion of the tube is surrounded by an air space by which the smoke passing through the tube is moderately cooled before passing to the outlet end of the pipe. The tube, as shown in Figure 4, may be said to be "floating" as the major portion of the length is free of any support. 75

In use, the smoke from burning tobacco is drawn from the bowl through the duct 16 80 into the pocket 15 and any moisture or tobacco bits present therein is trapped in the pocket and the smoke allowed to pass into the tube in which it is cooled before finally entering the mouth of a smoker. After a 85 charge of tobacco has been smoked and the ashes emptied from the bowl, the smoker may blow a blast of air through the stem and by reason of the flared end of the tube, the blast of air will be deflected against the side walls of the pocket 15 and any trapped substance will be blown out through the duct 16. The pipe may be kept clean and dry 90 at all times which prevents the pipe from smelling strongly of nicotine or creosote. The bearing collar co-acts with the walls of the pocket and bore to effectively seal the pocket from the bore to prevent the seeping of moisture between the joint which keeps 95 the interior of the bore in a dry condition. 100

In Figure 3 of the drawings, I have shown a slightly modified form of tube 17' which has an enlarged cylindrical mouth 18' in lieu of the flare as shown in the other forms. The cylindrical mouth snugly fits into a recess 23 between the duct 16 and bore 14. Any moisture or tobacco bits drawn from the bowl will accumulate in the enlarged mouth from where they may be blown out by a blast through the stem.

The form of my invention shown in Figure 4 is similar to that shown in Figure 1, with the exception that the flared end 18 is freely suspended within the pocket 15 by inserting the other end in the mouthpiece. The bearing collar is entirely dispensed with in this form.

To dispense with the drilling of a pocket 15 of a different diameter than the bore 14, I mount a ring 24 within the bore against which the bearing collar tightly fits. In this form the tube is slightly shorter than the others heretofore mentioned and the tube is disposed in axial alignment with the bore 16. The action of the smoke and results derived is practically the same as that already mentioned, so that a further detail explanation of the several modifications is not believed necessary.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

40. 1. A smoking pipe comprising a bowl having a duct therein, a stem for said bowl having an enlarged bore therein, said bore providing a cooling chamber, said stem being also provided with a recess, which latter communicates with said bore and with said duct, a mouthpiece attached in said enlarged bore, and an inner tube terminally engaged in said mouthpiece and also terminally engaged in said recess, the medial portion of said tube disposed in said enlarged bore in spaced relation with the wall of the stem, said medial portion adapted to cool air passing therethrough and carrying smoke from the bowl of the pipe.
55. 2. A smoking pipe comprising a bowl having a duct therein, a stem for said bowl and provided with an enlarged axial bore, said stem having also a recess therein of less diameter than said enlarged bore and of greater diameter than said duct, a tube axially disposed in said enlarged bore and spaced from the wall of said stem, one end of said tube engaged in said mouthpiece, and a hollow cylinder on the opposite end of said tube removably engaged in said recess, said cylinder

being of greater internal diameter than said duct and providing a receptacle for moisture descending from said bowl.

In testimony whereof I have affixed my signature.
